UNITED STATES PATENT OFFICE.

AUSBERT H. WAGNER, OF CHICAGO, ILLINOIS, ASSIGNOR TO CHARLES KAESTNER AND AUGUST KAESTNER, OF SAME PLACE.

IMPROVEMENT IN GRINDING-MILLS.

Specification forming part of Letters Patent No. 38,795, dated June 2, 1863.

To all whom it may concern:

Be it known that I, AUSBERT H. WAGNER, of Chicago, in the county of Cook and State of Illinois, have invented a new, useful, and Improved Grinding-Mill; and I do hereby declare that the same is described and represented in the following specification and drawings.

To enable others skilled in the art to make and use my improved mill, I will proceed to describe its construction and operation, referring to the drawings, in which the same letters indicate like parts in each of the figures.

Figure 1 is an elevation of my improved mill. Fig. 2 is a plan or top view. Fig. 3 is a section of Fig. 1, cut perpendicularly through the center.

The nature of my invention consists in the improvements hereinafter described and claimed.

In the accompanying drawings, A is a metal bed-plate, supported by three legs, B B, which plate is made circular, with the shaft C firmly fastened in its center. The bed or stationary stone D is provided with a metal bushing, E, made in the form shown in Fig. 3, which bushing supports the stone by resting on the movable collar F, which is fitted to traverse on the shaft C, and is raised by the U-frame G, which has two arms passing up through the plate A, as shown in the drawings. The lower part of the frame G is curved downward, and rests on the lever H, which curves upward, so that the frame is free to rock on the lever in one direction, and the collar F is free to rock on the arms of the frame G at a right angle to the rocking of the frame on the lever, and the top of the collar F is spherical, so that the bushing of the stone will tilt or vibrate freely on it, (the collar F,) so that the rocking of the frame G on the lever, and the rocking of the collar F on the frame, and the free vibration of the bushing E on the collar, allows the stone D to adjust its surface to the surface of the revolving stone I with the greatest ease and freedom. The fulcrum of the lever H is the bracket J, fastened to the plate A, and the end of the lever H is hinged to the adjusting-screw K, which passes up through the stand L, and is provided with a hand-wheel nut, M. By turning this wheel the miller can

raise or lower the stone D at pleasure. There are two or more pins, N N, fastened in the under side of the stone D, and project down through the plate A to prevent the stone D from turning. The shaft C is perforated from the top, as shown at P, with one or more openings, R, for the grain which descends through P to pass out and between the stones, and when it is ground it passes out of the spout S. The cylindrical shaft T turns freely on the stationary shaft C, and is provided with a flange, U, to which flange the stone I is fastened, so as to be turned by the shaft T, which shaft is provided with a pulley, V, for a band from some moving power to operate the mill. The shaft T has four recesses on the inside, filled with the pieces of wood W W, which are pressed or adjusted to the shaft C by the set-screws X X, when required. To prevent the stone I from rising or being pushed up by the stone D, I cut a screw on the top of the shaft C, and fit the nut Y to it, and make a recess in the end of the shaft T for the lower end of the nut Y, as shown in the drawings, Fig. 3. The casing a around the stone D is fastened to the flange b on the plate A, and the casing c is fitted to the top of the casing a to cover the stone I. There are two brackets, d, fastened to the case a, to receive the ends of the standards e e of the hopper-frame, which standards support the top, f, as shown in the drawings. The hopper g is fitted into the top f, and the rear end of the shoe h is hung to the top of the lever i, which vibrates on the screw j in the bar k, between the standards e e, and is moved by the lever l, which vibrates on the screw m in the case c, and is operated by the tappets n n on the shaft T, and by the spring p, fastened to the bar k, and shown in dotted lines in Fig. 3. The front end of the shoe h is supported by the cord q from the shaft r, which is provided with a hand-wheel, s, to turn it and adjust the shoe. The grain falls from the shoe h into the funnel t, through which it passes down the opening P, and out through the opening R to the stones. There is a circular cup or trough, u, around the shaft C, above the opening R, to catch any oil which may run down the shaft and prevent it from coming in contact with the grain.

I believe I have described and represented my improvements in grinding-mills so as to enable any person skilled in the art to make and use them without further invention or experiment, and I will now state what I desire to secure by Letters Patent—to wit, I claim:

1. The nut on the top of the hollow shaft, to hold down the running stone and prevent the stationary stone from lifting or raising it.
2. In combination with the hollow station-

ary shaft, the metal bed-plate to which it is fastened.

In testimony that the foregoing is a specification of my improved mill I have hereunto signed my name before two witnesses.

AUSBERT H. WAGNER.
